G. H. CLARKE.

UNITARY FIRE ENGINE AND STREET SPRINKLER.

APPLICATION FILED OCT. 16, 1916.

1,261,100.

Patented Apr. 2, 1918.

UNITED STATES PATENT OFFICE.

GEORGE H. CLARKE, OF NEWARK, NEW JERSEY, ASSIGNOR OF ONE-THIRD TO OSWALD R. BOUTH, OF NEWARK, NEW JERSEY, AND ONE-THIRD TO CARL H. FOWLER, OF NEW YORK, N. Y.

UNITARY FIRE-ENGINE AND STREET-SPRINKLER.

1,261,100.

Specification of Letters Patent.

Patented Apr. 2, 1918.

Application filed October 16, 1916. Serial No. 126,052.

To all whom it may concern:

Be it known that I, GEORGE H. CLARKE, a citizen of the United States, residing at Newark, in the county of Essex and State 5 of New Jersey, have invented certain new and useful Improvements in Unitary Fire-Engines and Street-Sprinklers, of which the following is a specification.

My invention relates to a combination 10 fire-engine and sprinkling machine, which, in its preferred form, embodies a self-propelled vehicle carrying a pumping outfit, an engine for operating the pump and also the vehicle, and a tank which may be utilized 15 for sprinkling the streets at times and for furnishing water or a chemical fluid for fighting fires, spraying purposes and the like, at other times.

My improved construction is devised particularly for the purpose of economy in the 20 cost of construction and maintenance and an increased utilization of the outfit in comparison with fire-engines and street-sprinklers mounted on separate bodies. The apparatus 25 may be utilized for sprinkling streets of towns, for example, during the times when a fire-engine would be idle, but will be instantly ready for a fire call should one come in. The tank carried by the apparatus 30 serves the double purpose of a supply for street sprinkling and similar purposes and a supply for fire-extinguishing purposes, which may be instantly utilized on arriving at a fire and while connections are 35 being made to a hydrant or other external water supply. The pumping outfit is arranged to draw water from either the tank or an outside supply, at will, and also for filling the tank from an outside supply when 40 the tank requires replenishing. The apparatus is compactly arranged, so that the necessary parts may readily be contained in a single vehicle. To this end, the water tank in my preferred form of invention is located 45 at the rear of the construction and is so arranged as to form seats for the fireman or others riding on the apparatus.

The objects of my invention are to provide improved apparatus of the character 50 and for the purposes referred to, and further consist in the arrangement of parts and combination of elements hereinafter more fully set forth and claimed in the appended claims.

55 In order that a clearer understanding of

my invention may be had, attention is hereby directed to the accompanying drawings forming part of this application and illustrating somewhat diagrammatically certain embodiments of my invention. In the drawings Figure 1 represents a side elevation of a combined fire-engine and street-sprinkling apparatus and Fig. 2 is a top plan view of the same.

Referring to the drawings, my preferred 60 apparatus comprises a self-propelled vehicle or automobile 1 driven by a gasoline motor indicated diagrammatically at 2. The pumping apparatus consists preferably of a centrifugal or rotary pump 3 with which 65 may be associated a small vacuum pump 4 for priming the centrifugal pump 3. The pumping outfit may conveniently be mounted under the removable seat 5 for the driver. The water tank 6 is mounted to the rear 70 of the pumping outfit above the rear axle 7.

The engine 2 may be connected to propel the vehicle when the latter is running to a fire or is sprinkling the streets, and disconnected from the running connections and 75 connected to operate the pumping outfit when the apparatus has been brought to rest and the pumping outfit is to be used. A shaft 8 is illustrated as running rearwardly from the engine, which may be connected to rotate the rear wheels, or disconnected therefrom, by usual means. Shaft 8 is connected, preferably by a silent chain 9, to a clutch member 10, which may be shifted by a hand lever 11, to clutch in shaft 12 of 80 the pump 3, to operate the same from shaft 8. A parallel shaft 13 is rotated from shaft 12 by a chain or belt 14, and a belt 15 runs loosely over sheaves on shaft 13 and the shaft of vacuum pump 4. An idler 16 is 85 mounted on a lever 17, to be pressed into contact with belt 15 when desired, to cause the latter to transmit power to the vacuum pump shaft, to operate the latter.

The pump 3 is provided with an intake 100 connection 18, which may extend to a suitable point or points, such as the coupling 19 shown at the rear of the machine, for connection by hose to a hydrant or other source of water supply. This may be provided 105 with a valve 20. A pipe 21 also connects intake 18 with the tank 6, under control of valve 22, so that water from the tank may be supplied to pump 3 when desired. The intake side of pump 3 is also connected, ad- 110

jacent to the pump, to the vacuum pump 4, by a pipe 23.

On the delivery side, pump 3 is connected, through a four-way coupling 24, with the 5 delivery pipes 25, 25, having couplings 26, 26 on both sides of the machine, to either of which may be connected a hose for conducting water for fire-extinguishing, street-flushing, tree-spraying and other purposes. 10 Pipes 25 are provided with valves 27, 27. Coupling 24 is also connected, through valve 28, with tank 6, for filling the tank when desired.

The tank 6 is adapted to operate as a 15 street sprinkler when no other calls are made upon the machine, as stated above, and accordingly sprinkler-heads 29, 29 are provided beneath tank 6 and connected by pipes 30, 30 to the opening 31 in the bottom 20 of the tank. Pipes 30, 30 are provided with valves 32, 32, which are connected through lever and link mechanisms 33, 33 with the hand levers 34, 34 located in front of the driver's position. Sprinkler heads 29, 29 25 are preferably located at opposite sides of the apparatus so that the supply of water being sprinkled to either the right or left, or both, may be shut off, as desired.

A tank or receptacle 35 is preferably 30 mounted above the forward end of tank 6 to contain suitable chemicals which may be dumped therefrom into tank 6 by mechanism of usual character when it is desired to impregnate the water in tank 6 with 35 chemicals suitable for fire fighting purposes, spraying trees, or the like. Tank 6 suitably forms seats for the firemen and to this end may be provided with raised longitudinally extending portions 36 and 37 at the sides 40 on which the firemen may sit and a central longitudinally extending portion 38 of less height than the portions 36 and 37 to constitute a runway or floor portion between the seats.

45 The operation of the devices described will now be clear. When the apparatus is being utilized as a street-sprinkler, either or both of the sprinkler-heads 29 may be put in operation by the levers 34, 34. When 50 the apparatus arrives at a fire, water from the tank 6, either plain or impregnated with chemical from container 35, may be thrown on the fire by pump 3, valve 22 being open and valve 20 closed at the intake side, and 55 valve 27 on the side adjacent the fire open and the opposite valve 27, and valve 28, closed at the delivery side. While the supply in tank 6 is being used, the coupling 19 may be connected to an external source of 60 supply, if necessary, and water drawn from the same when the supply in the tank becomes exhausted. This external source of supply may be a hydrant, or fire plug, if the latter be available, or any other source, 65 such as a cistern, river or pond. In the

latter case, it is advisable to first prime the centrifugal or rotary pump 3 by means of the vacuum pump 4, as the centrifugal pump does not reach its maximum efficiency until it and the intake connection leading thereto have become filled with water. When it is necessary to prime the centrifugal pump, the idler 16 is pressed into contact with belt 15 to rotate the vacuum pump shaft, valve 20 being open and valve 22 closed. Pump 4 then creates a vacuum from the source of supply through pump 4, water from the source rising through connection 18 and being carried by its momentum into pump 3, by which it is pumped onto the fire, idler 16 being raised from belt 15 to disconnect the vacuum pump as soon as the centrifugal pump has been primed. For filling tank 6, valve 28 is opened, valves 27, 27 being closed.

It should be understood that my invention is not limited strictly to the form of construction described above by way of illustration.

What I claim is:—

1. In a unitary fire-engine and street-sprinkler, the combination of a vehicle, a tank thereon, so formed as to provide seats for occupants of the vehicle, sprinkler-heads beneath the same, valved connections for supplying said heads with water from said tank by gravity, when desired, and a pump with suitable connections for filling or drawing from said tank, and also for pumping water from an external source and 100 directing the same at an external object.

2. In a unitary fire-engine and street-sprinkler, the combination of a vehicle, a tank thereon having sprinkler heads beneath the same, valved connections for supplying said heads with water by gravity when desired, a chemical container connected with said tank to dump chemicals therein when desired, pumping means and connections therefrom for filling said tank 110 or drawing liquid therefrom, as desired.

3. In a unitary fire-engine and street-sprinkler, the combination of a vehicle, a longitudinally extending water tank thereon, at the rear of the vehicle, having raised side portions adapted to form seats for passengers, and a central longitudinal portion of less height, adapted to form a passageway to said seat portions, sprinkler heads and valved connections for said tank, and pumping means and connections for filling said tank or drawing liquid therefrom.

4. In a unitary fire-engine and street-sprinkler, the combination of a vehicle frame, a rotary pump, a vacuum pump, and a tank on said frame, valved intake connections for said rotary pump extending to said tank and adapted to extend to an external source, respectively, a connection between the intake side of said rotary pump and 130

said vacuum pump, valved connections extending from the delivery opening of said rotary pump to said tank, and to an external delivery opening, respectively, and 5 means for operating said rotary pump, and, when desired, said vacuum pump.

5. In a unitary fire-engine and street-sprinkler, the combination of a vehicle frame, a rotary pump, a vacuum pump, and 10 a tank on said frame, a power-shaft, means for operating therefrom said rotary pump, and, when desired, said vacuum pump, an intake connection for said rotary pump adapted to extend to an external source, a 15 valved passage extending from said connec-

tion to said tank, a passage extending from said connection to said vacuum pump, a four-way connection connected to the delivery opening of said rotary pump, and valved connections extending from said 20 four-way connection to said tank, and to a pair of external delivery openings, respectively.

This specification signed and witnessed this 3d day of October, 1916.

GEORGE H. CLARKE.
